[57] CLAIM

The ornamental design for a plastic container, as shown and described.

DESCRIPTION

FIG. 1 is a perspective view of the new design of the present invention;

FIG. 2 is a front elevational view of the new design of the present invention;

FIG. 3 is a left side elevational view of the new design of the present invention;

FIG. 4 is a top plane view of the new design of the present invention; and,

FIG. 5 is a bottom plan view of the new design of the present invention.

The rear elevational view is the same as the front elevational view.

The right elevational view is the same as the left elevational view.
